MERCURY-VAPOR RECTIFIER

Application filed February 16, 1929, Serial No. 340,443, and in Germany January 30, 1928.

This invention relates to improvements in metallic vapor electric current rectifiers and, more particularly, to the cathode construction thereof and to means for preventing the formation of excessive amounts of vapor therein.

It is well known that occurrence of the condition commonly called "short circuiting", which results from current flowing between adjacent anodes of an electric current rectifying structure rather than between an anode and the cathode thereof may be caused by the formation of excessive quantities of metallic vapor which condense on the anode to produce a spot having the characteristics of the cathode. It is, therefore, desirable that the formation of excessive quantities of metallic vapor, i. e., amounts greater than necessary to conduct an electric arc between the electrodes be prevented to avoid short circuiting or so-called backfiring within the rectifier. One of the causes leading to the formation of excessive amounts of metallic vapor is the action of the electric arc which travels over the surface of the cathode with considerable rapidity thereby heating the entire surface of the cathode above the vaporization point of the material used. Various attempts have been made to prevent such rapid movement of the arc with the attendant heating of the cathode by providing means for fixing the arc at some particular point on the cathode. Among the means proposed has been the provision of structures formed from materials having an especially high melting point and arranged within or adjacent to the cathode material, which means, in themselves, are not satisfactory. Continuous research into the causes and the means for preventing short circuiting, above referred to, have shown that the amount of metallic vapor produced may be reduced in a very large degree without fixing the arc.

It is, therefore, among the objects of the present invention to provide means for preventing the formation of an excessive amount of metallic vapor within an electric current rectifier without the provision of any means for fixing the arc.

Another object of the invention is to pro-

vide means for cooling the surface of the cathode material so that formation of the metallic vapor from the free cathode surfaces, with the exception of the point of attachment of the arc, is so far prevented that the cathode surface serves as a condenser for the vapor already produced.

Objects and advantages, other than those above set forth, will be readily apparent from the description and the drawings in which

Figure 1 is a partial cross-sectional view of a metallic vapor electric current rectifier embodying the present invention, and

Fig. 2 is a view similar to that shown in Fig. 1 but illustrating a modified form of the invention.

Referring more particularly to the drawings by characters of reference, a cathode 5 commonly comprising mercury is retained within a container formed by insulating portions 6 arranged about an aperture in the bottom portion 7 of a rectifier tank and depending therefrom. The space inclosed by the insulating walls 6 is shut off by a bottom plate 8 which, according to the present invention, is formed to provide a chamber 70 therein. A conduit 9 extending through the bottom plate 8 and connected with a coil of tubing 10 is connected to a source of supply for a cooling fluid (not shown) which is circulated through coil 10 and returned to the chamber within plate 8 by a connection 11 from which chamber the cooling fluid is discharged by a discharge conduit 12. To obtain rapid and uniform heat transfer from the cathode mercury, the coil 10 is preferably formed of material having a high heat conductivity coefficient such as copper, which may be coated with a non-amalgamable material such as chromium. In order, further, to protect the coil 10 from contact therewith or attachment thereon of the electric arc, a shielding plate 13 is arranged to rest upon the cooling coil 10 which therefore locates 85 plate 13 just below the surface of the cathode mercury. The shield 13 fully protects the coil 10 from occasional or accidental penetration of the electric arc through the cathode mercury 5 and is preferably formed of some 90

difficultly fusible material which does not form an amalgam with mercury.

Instead of forming the cooling means, as above described, as of a coil of tubing arranged within the cathode, the coil of tubing may be omitted, thereby decreasing the amount of mercury required for the cathode, as is shown in Fig. 2. When the cooling coil 10 is omitted, it is desirable that the protecting shield 13 be arranged immediately about the upper surface of the closure member 8 which is supplied with cooling fluids through an inlet 9. The shield member 13 may be dispensed with if the bottom plate 8 is made of some material having a high melting point. If desired, the bottom plate may be made of some material having a relatively low melting point such as iron, provided with projections of some difficultly fusible material extending into the mercury to furnish points to which the arc may become attached but in any event the portion thereof in contact with the cathode material should be of material having a high rate of heat conductivity.

It will usually be found that water is adequate for cooling purposes but in case a more intensive cooling of the cathode is desired, it will be understood that other cooling or refrigerating means may be supplied to the chamber within plate 8 and to the cooling coil in such manner that the surface of the mercury is cooled far below the vaporization point thereof and is thereby adapted to operate as a condenser for those portions of the mercury vapor coming into contact therewith. It is even possible to cool the mercury so much that it solidifies and the cooling means may be so arranged that only the upper surfaces or the center of the cathode are cooled.

Although only two embodiments have been illustrated and described, it will be understood that various other embodiments are possible, and that various changes may be made without departing from the spirit of the invention or the scope of the claims.

The invention claimed is:

1. In an electric current rectifier of the metallic vapor type, a liquid metallic cathode, a coil of tubing arranged within said cathode to provide a path for the circulation of a cooling medium therethrough, and a shielding plate of difficultly fusible material arranged intermediate the upper surface of said cathode and said cooling means to prevent attachment of the electric arc thereon.

2. In an electric current rectifier of the metallic vapor type, a liquid metallic cathode, a cooling device arranged within said cathode to provide a path for the circulation of a cooling medium therethrough, and a shielding plate of difficultly fusible material arranged intermediate the upper surface of said cathode and said cooling device to prevent attachment of the electric arc thereon.

3. In an electric current rectifier of the

metallic vapor type, a liquid metallic cathode, a cooling device arranged within said cathode to provide a path for the circulation of a cooling medium therethrough, said cooling device being composed of a material having high heat conductivity, and a shielding plate of difficultly fusible material arranged intermediate the upper surface of said cathode and said cooling means to prevent attachment of the electric arc thereon.

4. In an electric current rectifier of the metallic vapor type, a liquid metallic cathode, a coil of tubing composed of a material having high heat conductivity and arranged within said cathode to provide a path for the circulation of the cooling medium therethrough, and a shielding plate of difficultly fusible material arranged intermediate the upper surface of said cathode and said cooling means to prevent attachment of the electric arc thereon.

In testimony whereof we have hereunto subscribed our names this 8th day of January, A. D. 1929.
